United States Patent Office

Des. 194,815
Patented Mar. 12, 1963

194,815

DOCUMENT REPRODUCING APPARATUS

Howard K. Graves, 12 White Oak Lane, Fairport, N.Y.

Filed May 21, 1962, Ser. No. 70,276

Term of patent 14 years

(Cl. D61—1)

FIG. 4

FIG. 2

FIG. 3

FIG. 1 is a left-hand perspective view of a document reproducing apparatus showing my new design;

FIG. 2 is a left-hand side elevational view;

FIG. 3 is a front elevational view; and,

FIG. 4 is a top plan view.

The right side of the machine is substantially a mirror image of the left side, and the bottom and rear of the machine are substantially plain and unornamented.

I claim:

The ornamental design for a document reproducing apparatus, as shown and described.
